UNITED STATES PATENT OFFICE.

CHAUNCEY L. OLMSTEAD, OF WEST BROOKFIELD, MASSACHUSETTS, AND
ALBERT D. NASON, OF NEW YORK, N. Y.

CORSET.

SPECIFICATION forming part of Letters Patent No. 338,184, dated March 16, 1886.

Application filed December 26, 1885. Serial No. 186,662. (No model.)

To all whom it may concern:

Be it known that we, CHAUNCEY L. OLMSTEAD, of West Brookfield, in the county of Worcester and State of Massachusetts, and 5 ALBERT D. NASON, of the city and State of New York, have invented an Improvement in Corsets, of which the following is a specification.

Corsets have heretofore been made with the 10 bottom edge sloped upwardly to pass over the hips. This corset is known as a "cut-away hip-corset," and in this style of corset there have been vertical sections corded, extending from the top to the bottom of the corset beneath the arm and over the hip, and corded bands extending at the front and back of these 15 vertical sections and forming the lower edge of the corset at these places; and elastic gores have been made use of in various parts of the 20 corset.

Our invention is made with reference to obtaining a small amount of elasticity above the 25 waist and below the arm, to allow freedom for the upper part of the body, in connection with a horizontally-corded non-elastic section below the elastic gore and extending from the 30 waist portion to the hip, the object of this being to allow the corset above the hip to conform to the shape of the person without the edge of the corset cutting into the flesh and without the risk of the corset rolling up or 35 folding over at the edge immediately above the hip.

In the drawings, Figure 1 is a perspective 35 view of the corset. Fig. 2 is a section at the line xx . Fig. 3 is a section at the line yy ; and Fig. 4 is a section at the line zz of Fig. 1.

The steels and clasping devices at B and the eyelets at A are of ordinary character, and 40 the sections C and D and bosom-gores E are similar to those heretofore used, and there are sections F and G at the back part of the corset that are corded vertically, as usual.

The section H is corded vertically, and it 45 extends from the top to the bottom edges of the corset, and the same is united at one edge to the section D and to one end of the curved band K, that is corded longitudinally and forms

the lower portion of the corset at the front of the abdomen.

The section I is corded vertically, and it 50 extends from the top to the bottom edges of the corset, and at one edge it is united to the section G and to the end of the corded band L, that forms the lower edge of the corset at 55 the back of the hip.

Between the sections H and I there is an elastic gore, M, that extends above the waist and beneath the arm, and this elastic gore is attached at its edges to said sections H and I, 60 respectively, and between these sections H and I, and below the elastic gore M, is a gore or section, O, which is non-elastic and corded horizontally, and the same is firmly attached to the edges of the sections H and I, and said 65 corded section O forms part of the waist of the corset, so that said waist is not elastic; and below the waist the horizontal corded of the gore or section O allows such section to conform to the shape of the person by springing or bending outwardly between the waist 70 and the upper part of the hip. This horizontally-corded section would roll up and form a fold at the lower edge above the hip were it not for the sections H and I, at opposite edges 75 of the same, which sections H and I, being corded vertically, hold down the lower edge of the section O sufficiently to cause the corset to retain the proper shape.

This corset is especially adapted to persons 80 that walk or stand on their feet considerably, because it allows freedom of motion at the hips, and at the same time it supports the abdomen and the waist, and the upper part of the body is comparatively free in its motions, 85 because the elastic gore M yields to any movement of the muscles of the chest and arms, and the motions of the upper part of the body do not drive the cut-away hip-corset down upon the hips as is the case in corsets that 90 have not the elastic gores under the arm portions.

We claim as our invention—

In a corset having its lower edge cut away 95 to pass up over the hips, the combination, with the front and back sections and the bands K

L, of the vertical corded sections H I, extending from the top to the bottom of the corset above the hips, the elastic gore M, between the sections H and I and beneath the arm, and 5 the non-elastic section O, between the sections H and I, and extending from the bottom edge of the corset above the waist to the elastic gore M, substantially as specified.

Signed by us this 23d day of December, A. D. 1885.

CHAUNCEY L. OLSTEAD.
ALBERT D. NASON.
